United States Patent Office.

T. O. WILSON, OF FISHERSVILLE, NEW HAMPSHIRE.

Letters Patent No. 86,792, dated February 9, 1869.

IMPROVEMENT IN SASH-FASTENER.

The Schedule referred to in these Letters Patent and making part of the same.

To all whom it may concern:

Be it known that I, T. O. WILSON, of Fishersville, in the county of Merrimack, and State of New Hampshire, have invented a new and improved Sash-Fastener; and I do hereby declare that the following is a full, clear, and exact description thereof, which will enable those skilled in the art to make and use the same, reference being had to the accompanying drawings, forming part of this specification.

This invention relates to an improvement in sash-stops, the object of which is to provide a more simple arrangement of spring-bolt for locking the sash in any position, all the parts being arranged and attached to a plate, which may be readily attached to any window with but little labor.

In the accompanying drawings—

Figure 1 represents a sectional elevation of a window, with my improvements attached thereto, the section being taken on the line *x x* of fig. 2; and

Figure 2 represents a transverse section, taken on the line *y y* of fig. 1.

Similar letters of reference indicate corresponding parts.

A represents a plate for supporting the spring-bolt, and the operating parts, which is designed to be let into the face of the window-frame, flush with the said face, and in front of a recess therein, as represented in fig. 1.

B represents a spring-bolt, arranged to work through a hole in the said plate, to engage with holes C, arranged at suitable intervals in the sash, to be coincident with the said hole in the plate, when opposite thereto.

I prefer to provide a projection, D, on the plate, around the said hole, for the better guidance of the bolt.

E represents a stud, arranged on one side of the plate, for the support of a bell-crank, F, one arm of which takes into the rear end of the bolt, and the other is provided with a sliding notched arm, G, projecting

through the side of the casing into the room, and arranged to be hooked on to the edge of an escutcheon-plate, H, through which it passes, to hold it in position when in its innermost position.

The end of the said arm, or the end of the bell-crank to which it is connected, is provided with a coiled spring, I, attached by one end thereto, and by the other end, to a stud, R, also projecting from the plate A, and having a constant tendency to draw the bell-crank and arm G in the direction to keep the bolt B engaged with the holes C of the sash, thereby maintaining it in the locked position.

When it is desired to maintain it in the unlocked position, the notched arm G may be hooked on to the escutcheon-plate H, and when not so engaged, the spring will cause the bolt to drop into any one of the holes, as they are brought into coincidence with the bolt, by raising or lowering the sash.

The sash may be either provided with balance-weights, L, or not, as preferred, my improved sash-lock, or fastener, being equally applicable to both.

By this arrangement all the parts of the device, except the escutcheon-plate, are fixed to the plate A in such a manner that the labor of applying the same to a window is materially simplified.

I am aware that a spring-bolt, bell-crank, and sliding bar, have heretofore been combined in a window-fastening, and I do not therefore claim such combination; but

What I do claim, and desire to secure by Letters Patent, is—

The notched sliding rod G, slotted plate H, bell-crank F, spring I, bolt B, slotted plate A, and arms E K, constructed and arranged in the manner herein described, for the purpose specified.

T. O. WILSON.
